UNITED STATES PATENT OFFICE.

ROBERT WILLIAM SIMPSON, OF MEMPHIS, TENNESSEE, ASSIGNOR TO MECHANICAL DEVICES COMPANY, OF MEMPHIS, TENNESSEE.

FLUID-PRESSURE JACK.

Application filed March 13, 1925. Serial No. 15,223.

To all whom it may concern:

Be it known that I, ROBERT WILLIAM SIMPSON, a citizen of the United States, and a resident of Memphis, in the county of 5 Shelby and State of Tennessee, have invented certain new and useful Improvements in Fluid-Pressure Jacks, of which the following is a specification.

This invention relates to improvements in 10 jacks and it consists of the constructions, combinations and arrangements herein described and claimed.

An object of the invention is to provide a multiple stage, fluid-pressure machine for 15 the purpose of lifting objects, the lifting capacity being determined by the weight and character of the object, which consideration in turn will determine the size of the machine.

20 Another object of the invention is to provide a jack wherein the pressure of the actuating fluid is exerted upon both ends of a movable plunger simultaneously.

25 Other objects and advantages appear in the following specification, reference being had to the accompanying drawings, in which

30 Figure 1 is a side elevation of the improved jack, illustrating the use of a table therewith for the purpose of lifting such objects as automobiles.

35 Figure 2 is a central vertical section of the jack, the plunger being in the retracted position.

Figure 3 is a detail sectional view in which the plunger is in the fully extended position.

40 Figure 4 is a cross section on the line 4—4 of Figure 2.

Figure 5 is a cross section on the line 5—5 of Figure 2.

45 Reference has been made to the invention as an expansible-fluid machine. It is intended to operate the machine by means of a fluid under pressure as for example, oil, air, water, etc. In view of this circumstance the machine might well be termed a pressure-fluid jack.

50 In carrying out the invention provision is made of a cylinder 1 which is composed of upper and lower sections 2 and 3. The confronting ends of the sections have flanges 4 and 5 which are secured by bolts 6 or the

like, a suitable gasket being interposed if necessary.

The cylinder 1 is intended to remain perfectly rigid, and in fact the larger sizes of the jack will be imbedded in the earth approximately up to the hub 7 as shown in Figures 1 and 2. In the smaller sizes of the jack the cylinder 1 will constitute the 60 stationary member.

The hub 7 contains a packing 8 which is compressed by a gland 9 upon the application of pressure by nuts 10 on a plurality of studs 11 stationarily mounted in the hub. 65 The packing prevents the leakage of fluid under pressure past the plunger 12. The plunger is movable, and constitutes the element by which the lifting is done.

Internal enlargements 13 and 14 in the 70 upper section 2 of the cylinder 1 have a stabilizing function in respect to the movable plunger 12. The plunger is tubular, being composed of a length of suitable pipe. Both ends are threaded. The upper end carries a head 15 to which the table 16 (Fig. 1) may be suitably applied, the lower end carrying a cap 17. Both the head and cap provide closures for the ends of the tubular plunger. The cap 17 has a loose fit in the 80 lower section 3 of the cylinder and serves as a guide, supplementing the stabilizing functions of the enlargements 13 and 14 already mentioned.

A suitable cap 18 closes the lower end of 85 the section 3. A nut 19 in the axial center of the cap 18 provides the anchor for the stationary tubular piston rod 20. The upper end of the rod carries a stationary piston 21 which fits the interior of the tubular plunger 12 and in reference to which the plunger is movable.

The hub 7, and its associated parts, and the piston 21 are stationary elements between which the plunger 12 is slideable. 95

A plurality of vents 22 in the stationary piston rod immediately below the piston 21 provide for the relief to atmosphere of air or other substances that might be entrapped in the air space between the piston rod and tubular plunger. Such release would occur upon the upward movement of the cap 17 with the plunger. The hollow piston rod is open to the pit 23 at the bottom, and in 100

practice the pit may be of sufficient volume to receive the escaping air, or it may have an outlet to atmosphere.

Screwed into the piston 21 is a supply pipe 24, and screwed into the cap 18 is another supply pipe 25. These pipes supply fluid which is carried under suitable pressure in a reservoir 26. The reservoir contains oil upon which pressure is imposed by compressed air in a tank 26^a. The discharge of compressed air is controlled by a three-way valve 26^b. The respective pipes discharge the fluid so that upward pressure is exerted against the cap 17 and head 15, these parts constituting the first and second stage lifts.

The supply pipes 24 and 25 join a common pipe 27 with which other pipes 28 and 29 have connection. The first pipe leads from the small end of a differential valve casing 30 and has a globe valve 31, the second pipe leading from the reservoir and having a globe valve 32. The valve casing 30 also has a pipe connection 33 with the reservoir, which connection carries a globe valve 34.

A pipe 35 provides communication between an annular groove 36 in the enlargement 14 and enlarged end of the valve casing 30. The enlargement 14 carries a suitable packing 37 immediately below the groove 36. The plunger 12 has a suitable pipe connection 38 which furnishes communication with one side to the space beneath the cap 17. A packing and gland 39 make a tight joint where the connection 38 passes through the cap 17. A packing and gland 40 similarly provide a tight joint where the stationary piston rod 20 passes through.

Situated in the valve casing 30 is a differential piston 41, in other words a piston consisting of parts of different diameters. The piston is normally retracted as in Figure 2, but when the tubular plunger 12 rises to the height in Figure 3, fluid pressure from the first stage lift enters the groove 36 by virtue of the communication of the pipe connection 38, imposing a superior pressure upon the piston 41 so that it moves to the right and shuts off the supply of fluid to the common pipe 27. The valve 32 (Fig. 2) is normally closed.

The operation is readily understood. The jack is supposed to normally assume the retracted position in Figures 1 and 2. The head 15 of the movable tubular plunger 12 may be suitably equipped to lift any kind of object. It is not necessarily confined to act as a mount for a table 16 as in Figure 1, but may be equipped for other lifting purposes. All of the valves 31, 32 and 34 are now closed. The three-way air valve 26^b is open.

Upon desiring to extend the plunger 12 the operator opens the valves 31 and 34.

Fluid under pressure from the reservoir 26 now enters the common pipe 27 whence it is distributed to both pipes 25 and 24. These pipes discharge the pressure fluid in the space beneath the cap 17 and head 15 where it exerts a simultaneous lifting force upon both ends of the plunger 12. The cap 18 and piston 21 are perfectly rigid and stationary, and provide the abutments against which the pressure fluid acts. The respective faces beneath the cap 17 and head 15 are regarded as first and second lifting stages. It is to be noted that each stage has its individual supply of pressure fluid.

As the plunger 12 rises in respect to the stationary cylinder 1 and stationary piston rod 20 the air, oil or the like, that may be entrapped in the space between will be expelled at the vents 22 to the interior of the rod 20 whence it passes to the pit 23 which is regarded as the equivalent to atmosphere.

The movable plunger 12 and head 15 are held in any extended position by merely closing the valves 31 and 34. Should it be desired to lower these parts the valve 32 is opened and three-way valve 26^b is turned to permit the return of fluid from the first and second stages to the reservoir 26, and the escape of residual air from tank 26 to atmosphere.

Provision is made against the event of the operator failing to close either valve 31 or 34, or both, in order to stop the extension of the plunger 12. Such failure would result in the cap 17 ultimately striking the internal enlargement 14 and causing serious damage to the jack. As soon as the side opening of the pipe connection 38 registers with the annular groove 36, pressure from the first stage moves the valve piston 41 over to the right (Fig. 3), automatically closing the pipe 28 and shutting off the flow of pressure fluid to the pipes 24 and 25.

The value of the internal enlargements 13 and 14 and of the guide cap 17 is readily seen. These parts hold the movable plunger perfectly stationary when fully extended, and prevent any unsteadiness when subjected to side pressures. The cylinder 1 is shown imbedded up to the hub 7, but it is to be understood that the differential valve casing 30, the various pipe connections thereof and the reservoir 26 are not intended to be imbedded. These parts will be situated on the surface where access may be had thereto.

While the construction and arrangement of the improved jack is that of a generally preferred form, obviously modifications and changes may be made without departing from the spirit of the invention or the scope of the claims.

I claim:

1. A jack comprising a stationary cylinder, a piston in annular spaced relationship,

a plunger which is slidable in the space between the cylinder and piston, and means for stationarily mounting the piston within the cylinder and supplying fluid under pressure for the operation of the plunger.

2. A jack comprising a stationary cylinder, a piston in annular spaced relationship to the cylinder, a tubular plunger slidable in the space between the cylinder and piston, a tubular piston rod having vents adjacent to the piston, means incorporated in the cylinder in which said rod is anchored, thereby holding the piston stationary, a cap on the lower end of the plunger, a head on the upper end of the plunger, and a pressure fluid supply pipe passing axially through the piston rod and supplying a space between the piston and head thereby to extend the plunger, the air entrapped between the head and piston passing through the vents and out by way of the tubular piston rod and a space around the supply pipe.

3. A jack comprising a stationary cylinder having a cap at one end, a piston in annular spaced relationship to the cylinder, a tubular plunger slidable in the space between the cylinder and piston, a head closing one end of said plunger and opposing one side of the piston, a cap closing the other end of the plunger and opposing the other side of the piston, a tubular piston rod stationarily supporting the piston within the cylinder and having vents adjacent to the piston, means carried by the cylinder in which the piston rod is anchored and through which it has communication with the exterior of the cylinder, and a source of pressure fluid supply including pipes to discharge fluid simultaneously into the cylinder between the cylinder and plunger caps and into the plunger between the piston and plunger head, the latter supply pipe passing freely through the stationary piston rod in spaced relationship thereto and being secured to the piston and leaving a passage through which air may escape from the vents upon the advance of the plunger cap toward the piston.

4. A jack comprising a cylinder, a movable plunger having a cap which fits in the cylinder, an annular groove on the interior of the cylinder facing the plunger, a source of pressure fluid including a pipe discharging into the cylinder beneath said cap, a pipe connection providing communication from the side of the plunger above the cap

to the space between the cap, and means including a pipe for conducting the fluid from said groove when said plunger raises sufficiently in the cylinder to bring the side of said connection in registration with the groove thereby providing a pressure release.

5. A jack comprising a cylinder, a movable plunger having a cap which fits in the cylinder, an annular groove on the interior of the cylinder facing the plunger, a source of pressure fluid including a pipe discharging into the cylinder beneath said cap, a pipe connection providing communication from the side of the plunger above the cap to the space between the cap, and means including a pipe for conducting the fluid from said groove when said plunger raises sufficiently in the cylinder to bring the side of said connection in registration with the groove thereby providing a pressure release, and a differential valve operated by the fluid thus released to automatically shut off the supply of fluid to the cylinder.

6. A jack comprising a pair of tubular sections one of the sections having an internal enlargement at one end and at the opposite end having a corresponding internal enlargement and a hood, means including flanges and bolts by which the dissimilar sections are secured together to constitute a cylinder, a tubular plunger movable in the cylinder in contact with said enlargements, a packing gland associated with the hub to provide a joint around the movable plunger, a cap closing the lower end of the plunger being sufficiently large to engage the interior of one of the sections for guidance, a head closing the upper and closed end of the plunger, a piston situated inside of the plunger, a tubular piston rod by which the piston is carried, means included in the cap at the lower end of the last section having means in which the tubular rod is anchored and through which communication to the atmosphere may be had, vents in said tubular rod providing said communication from the interior of the plunger, and means to supply fluid under pressure for the operation of the plunger; said means including a pipe entering the cylinder cap for the discharge of fluid beneath the plunger and a pipe extending axially of the tubular rod and discharging above the piston so that fluid exerts pressure on the head at the upper end of the plunger.

ROBERT WILLIAM SIMPSON.
